UNITED STATES PATENT OFFICE.

JAMES S. DOYLE, OF NEW YORK, N. Y.

COUNTERBALANCED WINDOW.

1,076,753.

Specification of Letters Patent.

Patented Oct. 28, 1913.

Application filed January 29, 1907, Serial No. 354,624. Renewed May 20, 1909. Serial No. 497,329.

To all whom it may concern:

Be it known that I, JAMES S. DOYLE, a citizen of the United States, residing in the city, county, and State of New York, have 5 made a certain new and useful Invention in Counterbalanced Windows, of which the following is a specification.

This invention relates to counterbalanced windows.

10 The object of the invention is to provide a construction of counterbalanced windows which is simple and efficient, and wherein the window may be held in any position to which it may be raised or lowered.

15 A further object is to provide means for clamping and releasing the counterbalanced suspending cords whereby the window is raised or lowered automatically, when such cords are released, and are arrested and held in the position occupied thereby when the counterbalance cords are clamped.

20 Other objects of the invention will appear more fully hereinafter.

25 The invention consists substantially in the construction, location and relative arrangement of parts, all as will be more fully hereinafter set forth, as shown in the accompanying drawings, and finally pointed out in the appended claims.

30 Referring to the accompanying drawings and to the various views and reference signs appearing thereon, Figure 1 is a view in front elevation of a counterbalanced window embodying the principles of my invention 35 the counter. Fig. 2 is an enlarged view in section on the line 2, 2, Fig. 1, looking in the direction of the arrows. Fig. 3 is a view similar to Fig. 1 showing the counterbalance weights applied to the upper sash. Fig. 4

40 is an enlarged detail view in section on the line 4, 4, Fig. 2 looking in the direction of the arrows. Fig. 5 is a detached detail view of a counterbalance weight. Fig. 6 is a view similar to Fig. 1 showing another arrangement of sash cord clamping or holding device included within the scope of my invention. Fig. 7 is a view in vertical section showing a modified construction of counter-

45 weight and anti-noise device embraced within the scope of my invention.

50 The same part is designated by the same reference sign wherever it occurs throughout the several views.

55 The window frames in which the sash are mounted to slide up and down are formed

from metal plates or sheets bent to form hollow box girders having the sides thereof shaped to form channels or grooves and beads to receive and form guides for the sash. In the particular form shown, the 60 metallic box girder A, is provided with the channels B, C, with an intermediate bead D, the metal or plate being suitably bent or shaped to form such bead and channels. The channels B, receive and guide the sash 65 side bars of one window sash either the upper or the lower, while the bead D, receives and guides the side bars of the other window sash, said side bars being constructed and properly shaped to conform to the configuration of the channels and beads, or else being received in guiding pieces which are so shaped and conformed, as more fully set forth in my application for patent Serial No. 353,840 filed January 24, 1907. The 70 channels C, receive and guide the fitting for the sash curtain or shade. This construction and arrangement of the hollow metallic box girder and window sash is claimed in my application above referred to, and therefore 80 I make no claim thereto herein. The interior of the hollow metallic box girder forms a chamber in which, in accordance with my invention, is accommodated the sash counterbalance weight E, the edges of such weight 85 being suitably shaped to conform to the interior channel produced in the sides of the box girder by the formation of the exterior beads C, therein, whereby the counterbalance weight is guided in its up and down travel. 90

If desired, and in order to prevent undue rattle and noise, the counterbalance weights are provided with holes or recesses in the surfaces thereof which contact with the guiding surfaces of the channels in the box 95 girder in which such weights move, in which holes or recesses are placed some soft material, such as lead, wood or the like, as indicated at F, Fig. 5, and which fillings take the bearing contact with the guide channels of the box girder, and not only reduce the noise and rattle incident to the movements of the counterweights within the box girders under rough usage, as for instance in the case of windows for street or railway cars, but also serve to reduce the friction of the up and down sliding movements of such weights.

In Fig. 7, I have shown a modified construction of counterweight and anti-rat. 110

tle device wherein a rod A' extends through a transverse hole or opening in the counterweight B' and carries the blocks or pieces C', at its ends which take the bearing contact with the interior surface of the guiding channel of the box girder, and which thereby not only serves to guide the counterbalance in its up and down travel but also prevent noise and rattle of the 10 counterweight. Springs D', are interposed between the anti-noise bearing blocks C', and the weight B', and allow a limited yielding swing of the weight.

It is obvious that other constructions and 15 arrangements of counterbalance weights may be employed, but the forms shown and described are sufficient to illustrate the principles involved, and demonstrate a practical arrangement for the employment of 20 suspended counterbalance weights for window sash even in car structures.

The counterweights are connected to window sash by cords G. These cords may be arranged and connected in any suitable or 25 convenient manner. In one form of arrangement, to which, however, my invention is not to be limited or restricted, the cords G, operate around a pulley H, carried by the counterbalance weight E, and over pulleys 30 J, journaled in the upper end of the box girder, as shown. Thence the cords lead and are secured to the window sash. The particular manner of the arrangement of the sash may be varied throughout a wide 35 range. As shown in Fig. 1, the lower sash L, is designed to be raised and lowered, and hence the sash cords G, are connected to the upper corners of said sash, as at K. Where the lower sash is moved to effect the 40 opening desired, it may simply be moved upwardly in the side guides provided by the channels formed in the box girders, or such sash may be lowered into a pocket or recess adapted to receive the same. In the drawing, Fig. 1, I have shown the lower sash 45 provided with a glass panel W, in its upper half and an open or grated panel X, in its lower half, and normally, when the window is closed the lower half or grated portion 50 extends into a recess or pocket below the window opening. By raising the sash the grated portion is elevated out of the recess or pocket and affords the desired opening, while the grated panel protects against the 55 danger of accident due to thrusting the hands, arms or head out of the window. This is a particularly desirable construction and arrangement for street or steam railway cars, and for Pullman or other sleeping cars, 60 in which latter instance the trouble and annoyance of removable screen sections, such as are customarily employed is avoided. If desired the sash cords may be connected to the upper sash N, at the upper corners 65 thereof, as at M, Fig. 3, whereby the upper

sash may be lowered to effect the desired opening, or raised to close such opening.

It is obvious that still other modes of operation of the sash may be adopted where desired or required. I do not desire, therefore to be limited or restricted in this respect.

The relative weights of the counterbalance and of the window sash should be so proportioned that the window sash may 75 be moved easily, smoothly and readily up and down in their guide channels. Where the sash is to be raised to effect the opening the counterbalance should overbalance the weight of the sash and the friction of 80 the sash and counterweight in their respective guideways or channels, so that when the sash cord is released the sash will rise automatically under the influence of the overbalancing weight, and where the sash is to 85 be lowered to effect the opening, whether it be the upper or the lower sash, then the weight of the sash should overbalance the counterweight, and the friction. If desired the 90 weight of the counterbalance may just balance the weight of the sash and the friction, whereby the window sash may be readily and easily moved in its guides and maintained in whatever position to which it may have been moved, as clearly shown in Fig. 3. 95

The sash cord may be gripped or clamped and released in many specifically different ways. I have shown a simple and efficient arrangement, to which, however, my invention is not to be limited or restricted, wherein I provide blocks or bearings O, on the interior of the hollow box girders, and a wedge block P, is arranged to operate between the blocks or bearings O. The runs of the sash cord pass the sides of the wedge 105 block P, and the adjacent surfaces of the bearing blocks, as clearly shown. By raising the wedge block, the sash cord is released to permit the sash to move automatically up or down, as the case may be, or to 110 be raised or lowered in its guides, and by lowering said wedge block the sash cords are gripped or clamped, thereby holding the sash in the position to which it has been moved. Many other different forms of grip or clamp devices for the sash cord may be 115 employed without departure from the spirit and scope of my invention. The wedge block P, in the particular form shown, may be operated in many specifically different ways. I have shown a simple and efficient arrangement for accomplishing the desired object wherein the wedge block is provided with a transverse cam or oval shaped opening in which is arranged a similarly shaped 120 rotatable block Q, with which engages the bent end R, of a rod S, said bent end extending into a transverse slot or opening V, formed in said cam block. The other end 125 of such rod is connected to one member of 130

a spring clip or hand piece, indicated at T, in Fig. 1, and by the manipulation of which said rod is projected or moved endwise, thereby causing the bent end R, thereof, 5 which extends into the slot of the cam block Q, to rotate said block so as to raise the wedge block P, thereby releasing the normal gripping action exerted thereby upon the sash cord. When the spring clip 10 or hand piece T, is released the wedge block returns to its initial position and again wedges the sash cord against the blocks O, thereby gripping and locking the same, and hence holding the sash in the position occupied 15 thereby at the time the spring clip or hand piece T, is released. Where the box girder is so formed as to accommodate a window on each side of the same, as in the forms shown in the drawing, two wedge 20 block operating rods S are employed, said rods extending in opposite directions from the box girder casing to spring clips or hand pieces T, independent of each other, and each rod having a bent end projecting 25 into the slot or opening in the cam block, whereby said block may be rotated and the wedge block operated by either rod. This is particularly true where the same counterbalance weight is used for sash in windows 30 on opposite sides of the same box girder, though my invention is not to be limited or restricted in this respect. It will be obvious that the operation of one window will not interfere with the adjacent window 35 since the sash cord at only one side of the adjacent window will be released when any particular window is to be raised or lowered.

In Fig. 6, I have shown another arrangement 40 of sash cord clamping mechanism embraced within the broad scope of my invention, and wherein the sash cord G, is arranged to pass through a hole or opening in the end of a rod E', mounted to slide or 45 to be projected through a stop guide F', arranged to extend into the box girder A, whereby, by withdrawing the rod E', the sash cord G is drawn or wedged against the end of the stop guide F', and thereby 50 gripped or clamped. The rod E', may be operated by means of a lever G', arranged in suitable position to be grasped and rocked or swing whenever it is desired to open or close the window. This lever is 55 pivotally mounted upon a plate H', having a lug J', serving as a guide for the rod E', and through which said rod passes. A spring K', is interposed between lug J', and a collar L', carried by said rod, the tension 60 of said spring being exerted upon the rod E', in a direction to cause the sash cord to be gripped or clamped. Of course it will be obvious that the same lever G', may be connected to sash cord clamping rods 65 operatively connected thereto on opposite

sides of the pivot of said lever, and extending to opposite sides or edges of the window as shown.

Other forms and constructions of sash cord clamping or gripping devices may be 70 employed without departure from the spirit or scope of my invention.

From the foregoing description it will be seen that I provide an exceedingly simple and efficient construction and arrangement 75 of counterbalance for windows wherein by simply manipulating a spring clip or hand piece the sash to be raised or lowered is released and moves up or down, as the case may be, and is arrested and held in position 80 by releasing the spring clip or hand piece. Where no sash cord gripping or clamping device is employed and the weight of the counterbalance is so proportioned with reference to the weight of the sash as to hold 85 the sash, in whatever position to which it may be raised or lowered, no sash cord gripping device is necessary, as seen in Fig. 3.

While my invention is particularly well 90 adapted for use in steel street or railway cars, it is also applicable to windows generally, wherever used, and I do not desire, therefore to be limited or restricted in respect to the particular situation where the 95 same is to be used.

Having now set forth the object and nature of my invention, and a construction embodying the principles thereof, what I claim as new and useful and of my own invention and desire to secure by Letters Patent is:—

1. The combination with a hollow metallic box girder having the exterior surfaces of the sides thereof shaped to form guides, 105 a window sash mounted to slide in said guides, a counterweight arranged to move within said box girder, a cord connecting said counterweight and sash, a clamping device arranged and normally operating to engage 110 said cord, and means for releasing said clamp.

2. The combination with a hollow metallic box girder having the side walls thereof shaped to form interior and exterior guide 115 grooves, a window sash fitted to slide in the exterior grooves, a counterweight arranged to operate within the box girder and fitted to slide in the interior guide grooves, connections between the counterweight and the 120 sash and means for clamping and releasing said connections.

3. The combination with a hollow metallic box girder having the sides thereof shaped to form interior and exterior guides, 125 a window sash fitted to the exterior guides, a counterbalance weight arranged to operate within the box girder and fitted to the interior guides, bearing blocks carried by said counterweight, and connections between the 130

counterweight and the sash and means for clamping and releasing said connection.

4. The combination with a hollow metallic box girder having the sides thereof shaped to form guides, a window sash fitted to said guides, a counterweight arranged to operate within the box girder, a cord connecting said counterweight and sash, and means arranged within the box girder for 10 clamping and releasing said cord.

5. The combination with a hollow metallic box girder having the sides thereof shaped to form guides, a window sash fitted to said guides, a counterweight arranged to

operate within the box girder, a cord connecting said counter weight and sash, means arranged within the box girder for clamping and releasing said cord and means extending outside of said box girder for operating said clamping and releasing means. 15 20

In testimony whereof I have signed my name to this specification, in the presence of two subscribing witnesses, on this 24th day of January A. D. 1907.

JAMES S. DOYLE.
